UNITED STATES PATENT OFFICE.

CARL A. JACKSON, OF KANSAS CITY, MISSOURI.

TOOTH-BRUSH.

1,142,566.

Specification of Letters Patent.

Patented June 8, 1915.

Application filed June 27, 1914. Serial No. 847,655.

To all whom it may concern:

Be it known that I, CARL A. JACKSON, a citizen of the United States, residing at Kansas City, in the county of Jackson and State of Missouri, have invented certain new and useful Improvements in Tooth-Brushes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to tooth brushes, and has for its principal object to provide a fountain tooth brush wherein a dentifrice may be stored in the handle of the brush and fed to the head and bristles as required.

20 It is also an object of the invention to provide a brush of this character with a removable handle, so that when the dentifrice has become exhausted, the handle may be removed and refilled or replaced.

25 In accomplishing these objects, I have provided improved details of structure, the preferred forms of which are illustrated in the accompanying drawings, wherein:—

Figure I is a perspective view of a brush embodying my invention. Fig. II is a longitudinal, sectional view of the brush. Fig. III is an enlarged sectional view, indicating the delivery of dentifrice to the bristles. Fig. IV is a sectional view of the handle.

35 Referring more in detail to the drawings: 1 designates a tooth brush constructed according to my invention and comprising a brush head 2, provided with bristles 3 and having an interior chamber 4.

40 The head 2 has a plurality of orifices 5 opening therefrom among the bristles 3, to provide outlet for the contents of the cham-

ber 4, and is provided, at one end, with a threaded neck 6, having an aperture 7 there-in communicating with the chamber 4, and 45 having exterior screw threads for applica-tion to the interiorly threaded neck 8 of a handle 9.

The handle 9 preferably comprises a sub-stantially rigid member 10 for forming the 50 top and sides thereof and a soft under por-tion 11 clamped thereto and forming a tube, for containing a dentifrice 12 in the form of a paste, or the like.

When using the brush, presuming the 55 handle to be filled and it is desired to dis-charge some of the dentifrice to the bristles, the soft under portion of the handle is com-pressed, thus forcing the dentifrice through the apertured neck portion into the chamber, 60 where it is emitted through the orifices among the bristles and is applied to the teeth. After all the dentifrice has thus been discharged from the handle, the handle may be removed and refilled or replaced by a new 65 handle.

Having thus described my invention, what I claim as new therein, and desire to secure by Letters-Patent, is:

In a tooth brush having a hollow head 70 provided with an exteriorly threaded tube and a plurality of apertures, a handle com-prising a rigid, channeled body having an end duct threaded onto said tube, and a rela-tively soft membrane seamed to the edges of 75 said channeled body, for the purpose set forth.

In testimony whereof I affix my signature in presence of two witnesses.

CARL A. JACKSON.
